CARBURETOR

George R. Ericson, Kirkwood, Mo., assignor to
Carter Carburetor Corporation, St. Louis, Mo.,
a corporation of Delaware

Application June 11, 1940, Serial No. 339,906

8 Claims. (Cl. 261—83)

This invention relates to carburetors for internal combustion engines and more particularly concerns novel fuel metering and atomizing mechanism therefor.

It is an object of the invention to provide new and improved means for metering the fuel so as to introduce the correct amount of fuel into the air stream over a wide range of air velocity. It is a further object to insure the co-mingling of fuel as it aspirates into the air stream so as to produce a thoroughly homogeneous mixture at extremely low velocities as well as at other times.

Other objects and advantages will appear upon reference to the following detailed description and accompanying drawing referring to which:

Fig. 1 is a diagrammatic representation of a carburetor embodying a form of the present invention. The view corresponds to a sectional elevation, and some conventional features of present day carburetors are omitted as they are well understood and have no direct bearing on the present invention.

The reference numeral 1 indicates the main body member of a carburetor which has a flange 2 at its lower end by means of which it may be attached to the intake manifold of an internal combustion engine. A mixture passageway 3 is formed through the main body member and an adjacent fuel chamber 4 is formed integral therewith. A main air inlet is indicated at 5, being formed in a combination air inlet and fuel chamber cover member 6. The member 6 is firmly attached to the main body member 1 by any suitable means (not indicated) and a sealing gasket 7 is provided therebetween. A conventional float 8 pivoted at 9 acts upon a fuel inlet valve 10 to maintain a substantially constant level of fuel in the chamber 4 as indicated by the dot-dash line A—A. An atmospheric vent to the fuel chamber is indicated at 11.

The fuel mixing conduit 3 is provided with a Venturi form constriction 12 and the lower or outlet end of the mixing conduit is controlled by a butterfly type throttle valve 13 mounted for rotation with a shaft 14. Concentrically disposed within the upper portion of the mixing conduit and supported therein by transverse ribs 15, is a circular member 16 having a frusto conical shaped discharge basin 17 formed therein. Extending upwardly through the basin 17 to approximately the level of fuel, is a stationary discharge nozzle 18. The upper rim of basin 17 extends to a point somewhat above the level of fuel. The mixing conduit is further provided with an annular recess 19 surrounding basin 17.

5 A rotary member 22 having a frusto conical shaped lower end is suspended in basin 17 by means of a shaft 23 in such manner as to leave an annular space 24 between the rotary member and the basin.

Shaft 23 carries a turbine 25 keyed thereto. The shaft 23 is driven by an electric motor 26 supported on a spider 27. The rotary member 22 is provided with outwardly and upwardly extending passages 22a which are directed toward the upper open end of annular recess 19. Member 22 is further provided with a tapered vertical bore forming a chamber 28 and receiving nozzle 18. The lower end of this tapered bore is made somewhat larger than the diameter of nozzle 18 to permit fuel to flow from basin 17 to chamber 28. Fuel is supplied to nozzle 18 from fuel chamber 4 through passage 30, chamber 31 and passages 33 and 33a. Passages 20 in ribs 15 and 10 cross holes 32 near the base of nozzle 18 permit the flow of fuel from recess 19 to nozzle 18. Under static conditions the recess 19, the basin 17 and the nozzle 18 are filled with liquid fuel to the level of line A—A. It will be noted that the 15 open end of recess 19 is above the upper edge of basin 17.

15 Fuel for idling operation is supplied to the mixing conduit through an idling system which comprises a passage 34 branching from passage 33, an idling jet tube 35 having a metering orifice 36 at the lower end thereof, passages 37, 38 and 39 and a discharge port 40 which opens into the mixing conduit near the upward opening edge of throttle 13. A calibrated air bleed 41 to passage 37 is provided. Fuel for all operation is metered through a calibrated restriction 42 situated at the lower end of passage 33. The net opening of orifice 42 is made variable by the provision of a variable diameter metering rod 43 arranged for 20 longitudinal adjustment with respect to said orifice. The metering rod 43, as shown, is provided with but two diameters, however, any number of steps or tapered portions may be added to suit individual fuel control requirements. Actuation 25 of the metering rod 42 is accomplished by provision of a flexible diaphragm member 44 to which the rod 43 is rigidly attached. The diaphragm member 44 forms a movable partition separating a chamber 31 formed as a recess in the main body member and a chamber 45 formed in a cover member 46. The chamber 45 is in communication with the mixing conduit at a point below the throttle valve by reason of a tube 47 and consequently is subject to substantially 30 engine intake manifold vacuum. A spring 48

normally urges diaphragm 44 toward a position whereby the chamber 31 is substantially evacuated and the metering rod 43 is moved to a less restricting position.

While the shape of the mixing conduit 3 and the air inlet conduit 5 are somewhat irregular in the diagram, it is to be understood that the greatest restriction and the zone of highest velocity is formed near the discharge outlets 22a of the rotary member, the member 22 itself forming part of the restriction. The various members forming this restricted portion may be streamlined as desired. Power for the operation of motor 26 is supplied by a storage battery 49 through a circuit comprising the leads 50, 51, 52, and 53. Interposed in this circuit is a vacuum responsive switch device generally indicated at 54. The switch device comprises a spring 54a which normally holds the switch in a circuit closing position. The switch device is arranged to respond to open at a predetermined intake manifold vacuum. A resistor 55 connected across switch 54 is provided and calibrated to permit the comparatively low speed operation of motor 26, even though switch 54 is open. A manual control switch 56 is also interposed in this circuit. The switch 56 may be the usual automotive ignition switch through which ignition devices (not shown) are connected.

In operation, when it is desired to start the engine, switch 56 is closed and the switch 54 will also be closed, there being no suction in the mixing conduit at this time to open this switch. Under these conditions the rotary member 22 will be rotated at comparatively high speed by means of motor 26. This action will cause fuel to be drawn into the chamber 28 and thrown therefrom by centrifugal force through passages 22 and transversely into the mixing conduit in the general direction of the open end of annular recess 19. A reduction in pressure in chamber 28 will result during high speed rotation of member 22 due to the flow through passages 22a which, in turn, is due to centrifugal force. This reduction in pressure will have the effect of drawing fuel from nozzle 18. The upwardly extending walls of chamber 28 being tapered outwardly will assist in raising fuel moving along their surfaces to the level of passages 22a. The similarly tapered lower outer walls of member 22 will likewise carry fuel upward from basin 17 to the air stream through the space 24. As the engine is cranked, the air flow through the carburetor will pick up the more finely atomized fuel discharged from passages 22a and also further assist in raising fuel to the level of passage 22a. The amount of fuel available to nozzle 18 under cold starting conditions may be increased by thermostatically control valve means, or the suction in the mixing conduit may be increased under these conditions by the provision of a thermostatically or manually controlled choke. Either of these means of temporarily enriching the mixture are well known and understood in the art.

When the engine begins to run under its own power ample suction will exist in the zone of member 22 to draw up sufficient fuel to operate the engine and this fuel will be thrown out into the air stream during that range of operation in which the vacuum in the mixing conduit posterior to the throttle is insufficient to open the circuit at switch 54. Any fuel which is not sufficiently atomized to be picked up by the air stream will be received in the annular recess 19 from which it will drain back to nozzle 18 through

passages 20 and the cross holes 32 therein. It will be noted that the bore of stationary nozzle 18 is so much greater than the size of the cross holes 32 that the flow of fuel or air through these openings will not prevent the drawing of fuel through the main jet 14. It will also be understood that the suction in the zone of the top of annular recess 19 will partially balance the suction on nozzle 18 so that the amount of fuel or air entering this nozzle through openings 32 will be somewhat retarded. This flow, however, will be aided by gravity in case, during operation, the level of fuel starts to build up in annulus 19. At normal and high air velocities fuel which drains into basin 17 will be drawn over the upper edge thereof.

In the present arrangement, the vacuum control switch 54 provides two operative speeds for the motor 26 and it is the intention to calibrate switch 54 in such manner that the higher rotative speeds of motor 26 and, consequently, impeller 25 and nozzle 22 will occur during operation when the vacuum in the mixture passage below the throttle is comparatively low, a condition which would be attended by comparatively low velocity through the carburetor. Low velocities through the mixture conduit will also occur, however, during idling with the throttle valve substantially closed at a time when the vacuum posterior to the throttle is comparatively high, but under these conditions, fuel is supplied through the idling system, being discharged at port 40 and, consequently, there would be no object in rotating nozzle 22 and impeller 25 at high speeds. By the insertion of the resistor 55 the motor and driven parts may be kept in motion at all times during engine operation thereby reducing lag due to inertia and rendering the device more responsive. It will be understood that any suitable device capable of gradually varying the speed of motor 26 in response to gradual variations in intake manifold vacuum may be used or the motor may be cut out entirely at the higher speeds. At high engine speeds, however, with the throttle substantially open, the flow through the air inlet will act upon the turbine 25 to greatly increase the speed of rotation of member 22, thus insuring high atomization of the fuel. Under conditions of high air stream velocity and consequent reduced pressure in the conduit, the switch 54 will be opened and the centrifuge will be driven by the turbine 25 acted upon by the incoming air. This arrangement obviously permits the conservation of electrical energy and provides a speed control of the centrifuge proportionate to the air stream velocity at these higher speeds. An additional pressure upon the fuel in passages 32 and 33 is exerted by the spring pressed diaphragm 44 when the manifold vacuum suddenly drops as in acceleration.

The foregoing description and accompanying drawing are intended to be illustrative not limiting and the use of all modifications of the invention within the scope of the following claims is contemplated.

I claim:

1. In a carburetor having a mixture passageway, a throttle valve for controlling the outlet of said passageway, a constant level fuel chamber, an electrically driven centrifuge device in said mixture passageway receiving fuel from said fuel chamber and discharging into said mixture passageway transversely to the direction of

flow therethrough, a control circuit for said centrifuge comprising a switch device responsive to vacuum in said mixture passageway posterior to said throttle for varying the speed of said centrifuge.

2. In a carburetor, a mixture passageway, a constant level fuel chamber, a centrifuge device in said mixture passageway adapted to discharge fuel into said mixture passageway transversely to the direction of flow therethrough, a source of power for driving said centrifuge, a fuel passage leading from said fuel chamber to said centrifuge, a suction operated fuel metering device capable of restricting the flow of fuel through said fuel passage as the suction in said mixture passageway is increased and a suction operated control device capable of reducing the speed of said centrifuge as the suction in said mixture passageway is increased.

3. In a carburetor having a mixture passageway, a constant level fuel chamber, a centrifuge device adapted to discharge fuel into said mixture passageway, a fuel passageway leading from said fuel chamber to said centrifuge device, and a spring opposed suction responsive device capable of discharging fuel under pressure into said centrifuge device when the suction in said mixture conduit is suddenly reduced.

4. In a carburetor, a mixture conduit, a throttle valve in said conduit, a centrifuge device adapted to discharge fuel into said passageway anterior to said throttle valve, a fuel passage leading to said mixture conduit and discharging therein posterior to said throttle valve, a source of power for driving said centrifuge, and a suction operated control device responsive to an increase in suction in said conduit posterior to said throttle valve for reducing the speed of said centrifuge.

5. In a carburetor, a mixture conduit, an air inlet to said conduit, a centrifuge device in said conduit adapted to discharge fuel therewith, a turbine in said air inlet arranged to drive said centrifuge when the air flow through said inlet is sufficient, an electric motor for supplement-

ing said turbine when the flow through said inlet is insufficient to drive the centrifuge at the desired speed, a source of electrical energy for driving said motor, and a pressure responsive control device responsive to decreasing pressures in said conduit to reduce the electrical current to said motor.

5 6. In a carburetor, a mixture passageway, an air inlet leading to said passageway, a fuel chamber, a centrifuge device receiving fuel from said chamber and arranged to discharge fuel into said passageway, a turbine in said air inlet and operated by the flow therethrough for driving said centrifuge, separate means for driving said centrifuge, and means responsive to the pressure condition in said mixture passageway for controlling said last mentioned driving means.

10 7. In a carburetor, a mixture passageway, an air inlet leading to said passageway, a fuel chamber, a centrifuge device receiving fuel from said chamber and arranged to discharge fuel into said passageway, means operated by the energy of the air passing through said air inlet and independent additional means for driving said centrifuge, and means responsive to the pressure condition in said mixture passageway for controlling one of said driving means.

20 8. In a carburetor, a fuel chamber, a vertical mixture passageway, a concentric air inlet leading to said mixture passageway, a concentric shaft extending from a point exterior of said carburetor through said air inlet and into said mixture passageway, an electric motor having its armature carried at the exterior end of said shaft for driving said shaft, a centrifuge device carried on said shaft and in said mixture conduit, said centrifuge being constructed and arranged to discharge fuel into said mixture passageway, means for conducting fuel from said fuel chamber to said centrifuge, and a turbine carried by said shaft and in said air inlet and arranged to be driven by the flow therethrough.

GEORGE R. ERICSON.
